HANDLE FOR A STORM WINDOW GLASS INSERT

Edwin R. Thompson, Canfield, Ohio, assignor to Western Reserve Plastics, Inc., Canfield, Ohio

Filed June 6, 1961, Ser. No. 65,481

Term of patent 3½ years

(Cl. D10—8)

FIG. 1

FIG. 2

I claim:

The ornamental design for a handle for a storm window glass insert, as shown.
